SWEEPING ATTACHMENT FOR ROAD GRADERS

Filed Feb. 15, 1928

Fig. 1.

UNITED STATES PATENT OFFICE

GEORGE GARDNER, OF REDLANDS, CALIFORNIA

SWEEPING ATTACHMENT FOR ROAD GRADERS

Application filed February 15, 1928. Serial No. 254,430.

This invention relates to road working machinery, and has for an object the provision of a power-driven rotary brush adapted to be removably mounted upon the chassis of a road grader or other road working machine, so that the machine may optionally be used to perform the function for which it was designed, or as a rotary brush.

With the foregoing and other objects in view which will be made manifest in the following detailed description and specifically pointed out in the appended claims, reference is had to the accompanying drawings for an illustrative embodiment of the invention, wherein:

Figure 1 is a side elevation of a road grader having the power-driven brush of my invention mounted thereon.

Fig. 2 is a horizontal, sectional view of the road grader of Fig. 1, the plane of section being taken upon the line 2—2 of Fig. 1 with the direction of view indicated by the arrows.

In terms of broad inclusion, my invention contemplates a power-driven rotary brush adapted to be removably mounted upon any suitable road working machine, as for example, upon a road grader. When it is desired to use the road working machine to perform the function for which the machine was primarily designed, the brush is susceptible to being readily removed; and when it is desired to use the power-driven brush, it may be mounted in operative position and connected to the motor and the blade, or whatever tool or tools the machine ordinarily carries may be either withdrawn or removed so that the brush may be used without interference from such tools. Or, if it be so desired, the brush and these tools may be employed simultaneously.

For the purpose of clearly setting forth my invention, I have shown its preferred embodiment as being mounted upon a road grader indicated in its entirety at 6. This grader being of the conventional type, is supplied with a scraper blade 7 removably mounted upon a mold board 8, which is rigidly carried upon a pair of arms 9 extending downward from a turntable 11. The turn-

table 11 is mounted for rotary movement about a circular member 12 which is fixed against rotary movement but which is capable of vertical adjustment in regard to either or both sides. This is effected by mounting the circular member 12 upon a length of angle iron 13, which is pivotally connected to the chassis 14 of the grader 6 at its forward end for vertical movement, and by supporting the circular member 12 upon each side by a link 16, each of which may be vertically adjusted by turning an associated control wheel 17; it being understood that the necessary operative connections between each control wheel 17 and its link 16 are included. Since the structure so far described is well known in the art, I am laying no claim thereto.

My invention comprises a rotary brush 21 capable of being removably mounted upon a road grader such as that above described, or other road working machine. The brush 21 is mounted for rotation within a bracket comprising a pair of spaced arms 22, each of which comprises a longitudinal section 23 and a transverse flange 24 extending therefrom. A bolt 26 is adapted to extend through an aperture in each of the flanges 24, and an aperture in the mold board 8 of the road grader whereby the arms 22 may be removably positioned upon the mold board to extend forward thereof longitudinally of the road grader. A platform 27 is rigidly secured to the after side of the mold board 8, being supported thereupon by stays 28; and a motor 29 is mounted upon the platform 27. The drive shaft 31 of the motor 29 is provided at its outer end with a beveled gear 32 enmeshed with a beveled gear 33 upon a countershaft 34 which is mounted for rotation within a journal 36 carried by the platform 27, and a journal 37 carried by one of the arms 22. The other end of the countershaft 34 is provided with a beveled gear 38 enmeshed with a beveled gear 39 mounted upon the shaft 41 of the rotary brush 21. Thus it may be seen that the brush 21 may be rotated by power furnished by the motor 29.

Preferably, the arms 22 are so positioned upon the mold board 8 that the lower portion

100

of the brush will be positioned lower than the bottom edge of the mold board 8 and higher than the lower edge of the blade 7. The purpose of this arrangement is to make 5 it possible to remove the blade 7 from the mold board and then operate the brush 21 with the lower edge of the mold board 8 sufficiently elevated above the surface being worked, so that it will not interfere with the 10 normal operation of the brush. When it is desired to use the machine as a grader, the blade 7 is replaced, and then the brush 21 may be removed by disengaging the bolts 26, which will permit complete removal of the 15 brush 21 and arms 22. The journal 36 is preferably of such design that the countershaft 34 may be completely removed therefrom when the brush 21 is dismounted.

It may thus be seen that a power-driven 20 rotary brush is provided, and that the manner of mounting the brush is such that it is capable of being adjusted not only in respect to its degree of angularity with the longitudinal axis of the grader, but also is capable 25 of having either or both ends of the brush adjusted vertically. The former adjustment may be effected by turning the turntable 11 upon the circular member 12; and the latter adjustment may be effected by operating the 30 proper one of the wheels 17, both adjustments being made in the same manner as when they are being made to the scraper blade of the road grader.

Various changes in the details of construction 35 may be made without departing from the spirit and scope of the invention as defined by the appended claims.

I claim:

1. In a device of the character described, a 40 bracket, a rotary brush mounted for rotation upon said bracket, means for removably mounting said bracket upon the mold board of a road grader, a motor adapted to be mounted on said grader and disconnectible 45 means for operatively connecting said motor to said brush.

2. In a device of the character described, a bracket, a rotary brush mounted for rotation upon said bracket, means for removably 50 mounting said bracket upon the mold board of a road grader with said brush extending below the lower edge of said mold board, a motor adapted to be mounted on said grader and disconnectible means for operatively connecting said motor to said brush.

3. In a device of the character described, a bracket adapted to be removably secured to the mold board of a road grader, a rotary brush revolubly mounted on said bracket, a 60 motor adapted to be mounted on said mold board, and disconnectible means for connecting said motor to said brush.

4. A road working machine comprising a 65 chassis, running gear therefor, a rotary brush, motor for rotating said brush, and

means mounting said brush and motor upon said chassis, said mounting means being adjustable to vary the angularity of said brush with the horizontal.

5. A road working machine comprising a 70 chassis, running gear therefor, a rotary brush, a motor operatively coupled thereto, and means mounting said brush and motor upon said chassis, said mounting means being vertically adjustable to vary the elevation of 75 said brush.

6. A road working machine comprising a chassis, running gear therefor, a rotary brush, a motor operatively coupled thereto, and means mounting said brush and motor upon 80 said chassis, said mounting means being adjustable about a vertical axis to vary the angularity of said brush with respect to the direction of travel of the chassis.

In testimony whereof I have signed my 85 name to this specification.

GEO. GARDNER.
